UNITED STATES PATENT OFFICE.

WILLIAM H. MILLSPAUGH, OF SANDUSKY, OHIO.

SUCTION ROLL.

Application filed July 24, 1925. Serial No. 45,828.

This invention aims to provide an improved construction for suction rolls and the like, having reference more particularly to the manner of mounting the cylinder and 5 suction box.

The invention will be understood by reference to one illustrative embodiment thereof shown in the annexed drawings.

In said drawings:

10 Fig. 1 is a longitudinal vertical section of one practicable type of suction roll embodying the invention. This section is taken on the line 1—1 of Fig. 2, looking in the direction indicated by the arrows.

15 Fig. 2 is a cross section on the line 2—2 of Fig. 1.

Fig. 3 is a detail vertical section through one of the journal-supporting rollers.

The structure selected for illustration is 20 a suction roll of the general type disclosed in the Millspaugh reissued Patent No. 13,100 dated April 12, 1910, equipped with an internal stationary suction box of the type disclosed in the Millspaugh Patent No. 25 1,025,822, dated May 7, 1912.

The rotating cylinder of said structure is designated in the drawings by the reference numeral 1; and its stationary member or suction box is designated by the numeral 2.

30 The cylinder is represented as a metal shell which is perforated or foraminous between its end portions, for a purpose which is well understood. The suction-box 2 is shown constructed with a trough-shaped upper portion having longitudinal packings 3 (Fig. 2) which bear against or coat with the interior surface of the cylinder, and having 35 adjustable end packing heads 4. It is understood that a vacuum chamber 5 is thus provided in the upper trough-shaped part 40 of the suction-box, said chamber communicating through the central opening 6 with the interior of the main portion of the suction-box, as explained in said Patent 1,025, 45 822. The ends of the suction box are shown interiorly screw threaded at 7 for connection with pipes leading to a vacuum pump.

Instead of mounting the cylinder in pedestal supports having annular bearings, as 50 is the case of the structures shown in the previously mentioned patents, the cylinder 1 of the illustrative structure is mounted by means such for example as shown in the drawings and now to be described. The cylinder journals, which in this instance are 55 enlarged journals provided by hardened

steel bands 8 shrunk or otherwise affixed upon the cylinder, bear upon and are supported by large surface-hardened steel rollers, there being a pair of such rollers 9 and 10 for each cylinder journal (Fig. 2). Said rollers are shown as of large diameter in relation to the cylinder and arranged at such appropriate distances at opposite sides of the vertical center of the cylinder as to afford 60 an adequate supporting bearing for the cylinder.

Each pair of journal-supporting rollers 9 and 10 is carried by a saddle 11 which is desirably supported as hereinafter explained 70 with capacity for a slight pivotal and rocking movement to permit self-adjustment of the supports for aligning the journal-supporting rollers with the cylinder. In the specific form shown, the saddles 11 comprise 75 castings which are approximately T-shaped at the center, i. e. midway between the rollers, as shown in Fig. 1, and which are substantially U-shaped at the ends, as shown in Fig. 3. By reference to Figs. 2 and 3 80 it will be seen that the rollers 9 and 10 are arranged between the vertical walls 12 of the U-shaped ends of the saddles, which walls are provided with substantial seats 13 for the roller shafts 14.

85 One of the individual journal-supporting rollers is shown in Fig. 3. As shown, it comprises a thick annulus, i. e. an annulus of large dimension between its inner and outer circumferences, and contains antifriction bearings designated as a whole by the numeral 15. These bearings may comprise concentric race-rings and interposed balls or rolling elements, all of hardened steel; the outer race-rings of the bearings being fitted securely in the roller 9, and the inner race rings being secured on the shafts 14. The bearings are housed in and protected by the rollers, which are shown closed at the ends by countersunk closure caps 16.

100 It will be understood that the rollers 9 and 10 at each end of the suction roll are equipped with such antifriction bearings, so that the cylinder will rotate on the large supporting rollers which in turn rotate on the annular series of rolling elements interposed between the interiors of the rollers and the shafts 14. Thus the cylinders may rotate 105 very freely and may be operated at high speeds with minimum consumption of power 110 over that required to drive the cylinder past the arc of vacuum.

Referring to the antifriction bearing feature, the construction shown is such as to permit the use of stationary shafts 14, which if desired may be positively held stationary by appropriate means, for instance pins 17. The shafts being comparatively short and stationary, such slight shaft flexing as may occur under the load of the cylinder will be of negligible effect since it will have no tendency to set up crystallization such as would accompany the flexing of a loaded rotating shaft.

For lubricating the antifriction bearings, the roller shafts 14 may each be provided as shown in dotted lines in Fig. 3 with an oil or grease passage 18 communicating with the roller chamber containing the bearings. Lubricant may be supplied by inserting the nipple 19 of a grease-forcing device into the end of the passage 18.

As before stated, the saddles 11 carrying the journal-supporting rollers are so mounted as to permit self-aligning of the rollers with the cylinder journals. For this purpose, the bottom of each saddle may be formed as shown with a central projecting rest 20 and end rests 21 which are machined and bear upon similar rests on base supports 22, which supports in this instance are the bottoms of the housings 23. The rests are slightly relieved to permit slight lateral rocking of the saddle, and the saddle has a central pivot stud 24 swiveled in an opening in the base. Thus the supporting rollers will accommodate themselves to the cylinder journals.

The housings 23 may comprise metal castings of the general character shown in Fig. 2, and which in this instance are shown having bottoms to support the saddles, which of course could rest directly on machine rails on which the housings are mounted. The housings when thus formed with bottoms are desirably provided with removable back walls 25 for access to the bearings.

Said housings 23 are constructed with their upper portions of semi-circular form to receive the cylinder journals 8, there being clearance between said journals and the semi-circular upper edges of the housing walls so as to avoid any frictional contact. The housings are capped with semi-circular caps 26 covering but not contacting with the cylinder journals and secured to the housings by stud bolts 27 as shown in dotted lines in Fig. 1 and full lines in Fig. 2. It will be observed that these housings with their caps 26 form separable supporting and housing structures which enclose the cylinder journals and contain the supporting devices or saddles 11 carrying the large journal-supporting rollers 9 and 10. Thus the structures have the general form and semblance of ordinary pedestal bearings, but it will be noted in this instance the

cylinder-journals are free of engagement with said structures or any fixed bearing surfaces and bear only on the antifrictionally journaled large rollers.

For supporting the suction box 2 from the housings, said housings are shown formed or constructed with the lower half-members 28 of clamp rings, the upper semicircular members 29 of which are secured to said lower members by stud bolts 30 shown in dotted lines in Fig. 1. The clamps composed of the members 28 and 29 embrace

circular heads or supports 31 in which the ends of the suction box are guided for radial adjustment and supported on the springs 32 in the manner shown in the previously mentioned patents. It will be understood of course that this specific construction is shown in view of having illustrated the present invention in an embodiment comprising the particular type of suction roll structure described in said patents. With this construction, angular adjustment of the suction box is of course easily effected by loosening the bolts 30 and angularly adjusting the heads 31 in the clamps 28-29, which clamps and heads represent supporting means for the box carried by the structures in which the ends of the suction roll cylinder are mounted. The general construction of the heads 31 and means of mounting the suction box therein will be understood by reference to said reissued Patent No. 13,100; the yieldingly-supported suction box ends being appropriately guided in diametric ways in the heads for radial play of the box toward and from the interior of the cylinder, and the pressure of contact of the open face of the suction box with the interior surface of the cylinder being limited and regulated by adjustable stops represented by screws 33 carried by the heads. The specific means stated is of course representative of any appropriate means for the purpose. The heads 31 are shown adjacent the ends of the cylinder, thus furnishing a means to prevent endwise movement of the cylinder.

A driving spur gear 34 is shown secured in the cylinder at the right hand end in Fig. 1. The particular arrangement illustrated is such that the driving gear is located between the cylinder journal 8 and the corresponding head 31, the clamp for which is correspondingly offset from the housing 23. Otherwise the construction at the driving gear end of the suction roll is substantially the same as at the other end.

In Fig. 2 there is shown a comparatively large solid roller 35 which bears of its own weight on the cylinder journal opposite the right hand journal 10. Assuming that the suction roll is being rotated in a counter clockwise direction (as viewed in Fig. 2) the roller 35 will resist any impulse of the

cylinder to unseat from its bearing rollers under the initial impulse of the gear drive. Said roller 35 is shown housed in an extension 36 of the cap 26. Said roller 35 may 5 have slight play radially of the suction roll cylinder, as for instance by mounting its shaft in appropriate slotted bearings. It will be understood that such a roller may be provided at each end of the suction roll 10 structure.

There is shown in Fig. 2 an oil receptacle 37 on the upper side of the cap 26, which supplies oil to the cylinder journal. In view of the fact that the cylinder journal 15 is free from contact with ordinary bearing surfaces, and is only in rolling contact with the large supporting rollers 9 and 10, which are antifrictionally mounted on lubricated ball or roller bearings, no lubrication of the 20 cylinder journals is needed for the ordinary purpose of lubrication, i. e. to reduce friction between engaging surfaces. The present inventor has, however, discovered that in practice a certain wear of the surfaces of the 25 cylinder journals and supporting rollers takes place by the rolling contact of these surfaces under load of the cylinder, and presumably by slight slippage. It is accordingly desirable to supply oil to the 30 journals as indicated, or to the surface of one of the journal supporting rollers, so that a film of oil will form between the several 35 surfaces in rolling contact and thereby avoid the wear alluded to. The oil may be fed by wick 38 lapping the surface to which it is directly applied, in this instance the journal.

Obviously the present invention is not limited to the specific embodiment thereof herein 40 shown and described. Features thereof may be advantageously used in various different combinations and sub-combinations. The suction roll may of course be used for other purposes, e. g. for application of pressure 45 instead of vacuum.

I claim as my invention:

1. A suction-roll comprising, in combination, a rotating cylinder; a pair of comparatively large antifrictionally mounted 50 rollers having broad treads under each end of the cylinder; antifriction bearings for said rollers; the cylinder being supported wholly by said antifrictionally mounted rollers and free of contact with other bearing surfaces; a box cooperating with the cylinder; and means supporting the box in operative relation with the cylinder.

2. A suction-roll comprising, in combination, a cylinder and box cooperating there- 60 with; box supporting means; a pair of large antifrictionally mounted rollers supporting each end of the cylinder; and saddles carrying said rollers; said saddles adjustably mounted to permit self-alignment of the 65 rollers with the cylinder.

3. A suction-roll comprising, in combination, a cylinder and box cooperating therewith; end standards unprovided with cylinder bearing surfaces; antifrictionally mounted rollers supporting the cylinder 70 journals; supports for said rollers capable of play to permit self-adjustment of the rollers to the cylinder; and means carried by said standards supporting said box.

4. A suction-roll comprising, in combination, a cylinder and box cooperating therewith; box supporting means; and rollers on which the cylinder bears, said rollers having antifriction bearings and mounted to 75 permit self-alignment of the rollers with the cylinder.

5. A suction-roll comprising, in combination, a cylinder, end standards in which the cylinder is mounted, said standards free of engagement with the cylinder journals; 80 antifrictionally mounted rollers associated with said standards, on which rollers the cylinder journals bear in rolling contact; and means supported by said standards comprising means yieldingly forcing the 85 box toward or in contact with the cylinder and adjustable means limiting the pressure of contact.

6. A suction-roll comprising in combination, a cylinder; a box cooperating therewith; hollow end standards in which the cylinder is mounted; said standards having semi-circular edges close to but out of contact with the lower half of the cylinder; antifrictionally mounted rollers housed in said 90 standards, on which rollers the cylinder bears; and means supported from said standards carrying the box.

7. A suction-roll comprising, in combination, an open-ended cylinder having 105 journals of a diameter as great as that of the cylinder; large antifrictionally mounted rollers on which the cylinder journals bear in rolling contact, yieldingly mounted rollers cooperating with said cylinder to prevent 110 unseating of the journals from said first mentioned rollers; and a suction box supported in cooperative relation with the cylinder.

8. A suction-roll comprising, in combination, a cylinder and cooperating box; end standards having caps; said standards and caps forming separable structures having the general form and semblance of pedestal bearings and enclosing the cylinder journals 115 but clear of contact with said journals; and antifrictionally mounted rollers associated with said standards on which the cylinder journals bear.

9. A suction-roll comprising, in combination, a cylinder and cooperating box; end standards having caps; said standards and caps forming separable structures enclosing the cylinder journals; antifrictionally mounted rollers associated with said stand- 120 125 130

- ards on which the cylinder journals bear; and means carried by said caps cooperating with the cylinders to prevent unseating from its supporting rollers.
5. 10. A suction-roll comprising, in combination, a cylinder and cooperating box; end standards having caps; said standards and caps forming separable structures enclosing the cylinder journals; a pair of antifrictionally mounted rollers supporting each cylinder journal; and saddles associated with said standards, each carrying a said pair of rollers.
11. In a structure of the class described, 15 the combination with the cylinder, of a pair of antifrictionally journaled rollers supporting an end of the cylinder; a saddle carrying said rollers; and a housing in which the saddle rests; whereby the rollers may be 20 assembled and removed as a unit.
12. In a structure of the class described, the combination with the cylinder, of a pair of antifrictionally journaled rollers supporting an end of the cylinder; a saddle carrying 25 said rollers; said saddle mounted with capacity to pivot and tilt to render the rollers self-adjusting to the cylinder.
13. A structure of the class described having, in combination with the rotating perforated cylinder, supporting standards un- 30
- provided with bearing surfaces for the cylinder; caps affixed to said standards; said standards and caps forming separable structures enclosing end portions of the cylinder; and rollers housed in said standards on 35 which the cylinder has its bearings.
14. A structure of the class described having, in combination with the rotating perforated cylinder, supporting standards un- 40 provided with bearing surfaces for the cylinder; caps affixed to said standards; said standards and caps forming separable structures enclosing end portions of the cylinder; supporting rollers for the cylinder mounted in said standards; means carried by said 45 standards to prevent longitudinal displacement of said cylinder; and means carried by said caps cooperating with the cylinder to prevent unseating thereof from said supporting rollers.
15. In a structure of the class described, the combination with the cylinder, of supporting standards therefor unprovided with bearing surfaces for said cylinder; and self-adjusting means carried by said standards 50 for antifrictionally mounting the cylinder.

In testimony whereof, I have signed my name to this specification.

WILLIAM H. MILLSPAUGH.
